UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,251,091.

Specification of Letters Patent. Patented Dec. 25, 1917.

Application filed July 20, 1916. Serial No. 110,267.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

One of the objects of my invention is to provide efficient draft rigging. A further object is to provide a friction spring draft gear adapted to be employed in association with tandem draft rigging side castings.

In the drawings forming a part of this specification, Figure 1 is a side elevation, partly in vertical, longitudinal section of a draft rigging embodying my invention. Fig. 2 is a horizontal section partly in top plan. Fig. 3 is a cross section taken on line 3—3 of Fig. 1. Fig. 4 is a cross section taken on line 4—4 of Fig. 1. Fig. 5 is a perspective view of the friction shell, and

Fig. 6 is a perspective view of a section of the draft yoke.

Referring to the drawings, the numerals 7—7 indicate draft members or parts of the under-framing of the car to which the draft rigging is applied; 8—8 side plates secured by suitable means, as, for instance, the rivets 9—9 to the draft members. The draft plates are such as are employed in tandem spring draft rigging and each of said plates is provided with a front stop 10, a front limiting stop 11, a middle stop 12, a rear limiting stop 13, and a rear stop 14. The middle stops 12—12 are deeper than the end stops 10 and 14, respectively. Between the draft members is mounted a draw bar 15 provided with the usual upper and lower shoulders 16 and 17, respectively. A draft yoke 18 is secured to the draw bar and connects the same to the draft gear 19, which is mounted between the side plates. In tandem spring draft rigging, one compression resisting unit is mounted in the front pocket 20 formed between the front stops and the middle stops and another compression resisting unit is mounted in the rear pocket 21 formed between the middle stops and

the rear stops of the side plates. In the particular embodiment of my invention illustrated in the drawings, a friction compression resisting unit 22 is mounted in the front pocket and a spring compression resisting unit 23 is mounted in the rear pocket. 60 The friction compression resisting unit 22 comprises a shell 24 preferably of hollow, cylindrical shape having mounted therein the wedge 25, the annularly arranged friction shoes 26—26, the interposed anti-friction rollers 27—27 and a plunger 28 which rearwardly engages the friction shoes, is extended through the rear opening of the friction shell and passing between the middle stops 12—12 of the side castings, engages at 70 its rear end the rear intermediate follower 29.

The wedge is provided at its forward end with a recess 30 to receive the nut 31 of the connecting bolt 32 which passes through the wedge and through the plunger, the said connecting bolt being provided at its rear end with a head 33 to engage it to the plunger. The rear end 34 of the friction shell is, in normal position of the parts, seated 80 against the center stop 12. A front follower 35 engages the wedge and in normal position is seated against the front stops 10. The spring compression resisting unit 23 mounted in the rear pocket 21 comprises the 85 rear intermediate follower 29 and the rear follower 36, together with the springs 37 mounted between said followers. In normal position of the parts, the rear follower 36 engages against the rear stop shoulders 14. 90 The compression resisting elements are inclosed within the yoke 18, the particular form illustrated in the drawing being a two-part yoke or a yoke comprising two loops arranged side by side. The said loops are 95 interconnected at their forward ends by the inter-engaging hinge-forming parts 38—38 and are connected at their rear ends by the key 39 passing through the lugs 40 upon the yoke. The upper and lower limbs 41 and 42 of the yoke, respectively, are provided each with a front in-turned lug 43 and a spaced rear in-turned lug 44 providing a transverse groove 45 between the lugs. The inner portion of the lug 44 has a forwardly 100 extending flange 46 inclosing a portion of the transverse groove 45. The rear portion of the friction shell is provided with a pref-

erably integral follower 47 having the upper and lower rearwardly extended flanges 48 and 49 respectively, which, together with the adjacent portions of the said follower, 5 form a tongue adapted to enter an adjacent transverse groove 45 of the yoke.

At its forward end, the friction shell is provided with the upper and lower, preferably integral extensions 50 and 51 respectively, 10 the flat ends of which extend transversely along the inner faces of the yoke limbs. By reason of the tongue and groove structure provided upon the shell and yoke, the shell and yoke are held together on forward and rearward movement of the draft rigging. The yoke is provided with the lateral plates 52—52 which, together with the limbs, form a head within which the butt 53 of the draw bar 15 is received and 15 the limbs are also provided with the in-turned gibs 54 which engage against the draw bar shoulders 16 and 17. On rearward movement of the draw bar, the yoke remains stationary, the draw bar sliding rearwardly 20 therein, forcing the front follower against the wedge, which brings the friction shoes into operation, the rearward movement of the friction shoes being resisted through the medium of the plunger 28 by the spring 25 compression resisting unit 23. The springs in rearward movement of the draw bar are held at their rear ends by the rear follower 36 through its engagement against the rear 30 end stops 14. On forward movement of the 35 draw bar, the yoke is drawn forwardly, forcing the spring compression resisting unit into action, which, in turn, presses by means of the plunger, against the friction 40 shoes and the yoke through its engagement with the friction shell, draws the said shell forwardly, bringing the contained friction elements into compression resisting action, the same being held against forward movement by the front follower 35 which is 45 stopped by the front stop shoulders 10 of the side plates. A space indicated at the 50 numeral 55 in Figs. 1 and 2 of the drawing is provided between the rear intermediate follower 29 and the center stop 12, thus forcing the springs to act against the friction elements in forward movement of the draw bar until the rear intermediate follower 29 55 comes into engagement with the center stops 12. The entire draft gear is supported in its position between the draft members and stops by means of the tie plate 56 which is suitably secured to the draft members 7 as, for instance, by the bolts 57.

Thus I have provided a high capacity 60 friction draft gear in which a short friction shell may be employed and all the parts of which may be assembled with tandem draft rigging side plates so that cars provided with such side plates may have substituted therein without any change of stop 65

members, a high capacity friction gear, thus greatly increasing the shock absorbing capacity of the draft rigging.

I claim:

1. In a draft rigging for railway cars, in combination, stop members forming front and rear pockets, a compression resisting unit in each of said pockets, a yoke to connect said units to a draw bar, one of said units including a shell, the yoke and shell 70 being provided with means to prevent their relative, longitudinal movement.

2. In a draft rigging for railway cars, in combination, tandem draft rigging side plates, a friction compression resisting unit 80 in the one pocket thereof, a spring compression resisting unit in the other pocket thereof, a yoke to engage both of said units to a draw bar, the friction compression resisting unit including a shell, the said shell 85 being engaged to the yoke and held against relative longitudinal movement therewith.

3. In a draft rigging for railway cars, in combination, side plates having end and middle stops, a friction compression resisting unit between the middle stops and one set of end stops, a spring compression resisting unit between the middle stop and the other set of end stops, a yoke to connect both of said units to a draw bar, the 90 friction compression resisting unit including a shell, the said shell being rigidly engaged to the yoke.

4. In a draft rigging for railway cars, in combination, side plates having end and middle stops, a friction compression resisting unit between the middle stops and one set of end stops, a spring compression resisting unit between the middle stops and the other set of end stops, a yoke to connect both of 100 105 said units to a draw bar, the friction compression resisting unit including a shell, the said shell being rigidly and detachably engaged to the yoke.

5. In a draft rigging for railway cars, the 110 combination with tandem draft rigging side plates, of a friction shell and friction elements within the shell, springs and followers and a yoke to connect said parts to a draw bar, the friction shell being seated between 115 the middle stops and one set of end stops of the side plates, the springs being seated between the middle stops and the other end stops of the side plates, a plunger extending between the springs and the friction elements; said plunger passing between the middle stops of the side plates.

6. In a draft rigging for railway cars, the combination with side plates having end and middle stops, of a draw bar, a yoke connected 125 thereto, tandem arranged sets of compression resisting elements within the yoke, one set of compression resisting elements comprising a shell and friction parts within the shell, the other set comprising springs and followers, 130

the friction shell being mounted between the middle stop and one set of end stops, the springs being mounted between the middle stops and the other set of end stops and a 5 plunger passing between the middle stops and engaging the friction elements at one end and the spring elements at its other end.

7. In a draft rigging for railway cars, in combination, side plates having end and 10 middle stops, a draw bar, a yoke connected to the draw bar, two sets of compression resisting elements in tandem arrangement within the yoke, one set including a friction shell and friction elements within the 15 shell, a plunger extending longitudinally from said friction elements within the shell and operatively engaging the other compression resisting elements.

8. In a draft rigging for railway cars, in 20 combination, side plates having front, rear and middle stops, a draw bar, a yoke connected thereto, two sets of compression resisting elements in tandem arrangement within the yoke, the front set comprising a 25 shell mounted between the front end stops and the middle stops of the side plates, the rear set comprising followers and springs between the followers, all mounted between the middle stops and the rear end stops, a 30 plunger passing between the middle stops and engaging the friction elements at one end and the spring elements at the other end, the yoke and the shell being held together against relative longitudinal movement. 35

9. In a draft rigging for railway cars, in combination, side plates having end and middle stops forming front and rear pockets between the side plates, a yoke mounted between said side plates, a friction shell in one 40 of said pockets, springs in the other of said pockets, the friction shell having friction elements therein and a plunger extending between said elements and the spring elements, the friction shell and yoke having 45 inter-engaging means to prevent their relative, longitudinal movement, the yoke and shell being stationary in buffing action of the rigging and moving forwardly simultaneously on pulling action of the rigging. 50

10. In a draft rigging for railway cars, in combination, side plates having end and middle stops, a draw bar, a yoke slidably

connected to the draw bar, a friction compression resisting element between the front 55 end stops and the middle stops of the side plates, spring compression resisting elements between the middle stops and the rear end stops of the side plates, the friction resisting elements comprising a shell 60 and friction elements within the shell, the shell and yoke being provided with transverse tongues and grooves to hold the yoke and shell against relative, longitudinal movement. 65

11. In a draft rigging for railway cars, the combination with a tandem yoke having front and rear pockets, of a friction mechanism mounted in one of said pockets, said friction mechanism including a friction shell 70 interlocked with the yoke to prevent relative longitudinal movement therebetween, a spring mounted in the other pocket of said yoke, followers in said pockets, and stops cooperating with said followers. 75

12. In a draft rigging for railway cars, the combination with tandem stop castings, of a spring, a friction mechanism including a friction shell, the spring and friction mechanism being arranged in tandem, and a two-part yoke within which said spring and friction mechanism are mounted, said yoke and shell having inter-engaging shoulders arranged to move the shell in unison with the yoke. 80

13. In a draft rigging, the combination with tandem arranged stop castings, of a short friction shell having transversely extending upper and lower shoulders, friction elements co-operable with said shell, a two-part yoke within which said shell is mounted, the parts of said yoke when assembled having transversely extending grooves on the inner faces of the arms thereof within which are received said shoulders, whereby 90 the yoke and shell move in unison, a spring mounted within said yoke, and a thrust member extending from the friction elements to said spring. 95

In witness that I claim the foregoing I 100 have hereunto subscribed my name this 18th day of July, 1916.

JOHN F. O'CONNOR.
